DOOR STOP

Robert L. Sitts, Pontiac, Mich., assignor, by direct and mesne assignments, to Slip-Lok, Inc., Pontiac, Mich., a corporation of Michigan

Application February 27, 1939, Serial No. 258,781

4 Claims. (Cl. 292—76)

The invention relates to door stops and has for its object the obtaining of a construction which forms no obstruction to furniture resting on the floor. It is a further object to obtain a construction which in addition to forming a limiting stop, also serves to hold the door alternatively in a plurality of positions of angular adjustment. To this end the invention consists in the construction as hereinafter set forth.

10 In the drawing:

Figure 1 is a horizontal section through a portion of a door and the adjacent casing, illustrating my improved construction of stop as applied thereto;

15 Figure 2 is a sectional elevation showing the door in stopped position;

Figures 3 and 4 are plan views respectively of the door member and casing member detached.

20 My improved construction comprises generally a door member and a casing member, each of which is provided with locating means for engagement with the pin of one of the door hinges. Each member also has an angle flange for attachment to the door or casing and an outwardly projecting segmental flange. The segmental flanges are so arranged as to come into frictional contact with each other when the door is opened, the limit of movement being where the outer edge of one segmental flange contacts

25 with the angle flange of the other member.

In detail, A is the door member having a segmental flange A', angle flange A² and a projection A³ from the small end of the segmental flange which is slotted to engage with the hinge

30 pin. B is the casing member which also has a segmental flange B', an angle flange B² and a projecting slotted portion B³. Preferably, there

35 is an additional member C having a segmental flange C' and an angle flange C², which member

40 is placed adjacent to the member B and permanently secured thereto by suitable means, such as spot welding together the angle flanges thereof. The segmental flanges B' and C' are spaced from each other sufficiently to receive the segmental flange A' of the member A. The latter

45 is formed with a series of struck-out portions A⁴ which are adapted to successively register with a corresponding series of depressions C³ in the inner side of the member C. These depressions

50 are preferably extended radially of the segment with respect to the axis of turning so as to be engageable with the struck-out portions in slightly different positions. The arrangement is such that when the segmental flange A' is inserted

55 in the slot between the flanges B' and C', the

projections A⁴ will spring the latter flanges apart, but will form a latch engagement successively with the depressions C³ to hold the door in different positions of adjustment.

5 Door casings for different doors vary in thickness and the hinges for mounting the doors also vary in the location of the hinge bolt or pin with respect to the door and casing. My improved construction of door stop is universally applicable to all of these variations, due to the specific construction of the locating means. Thus it will be observed that the slot in the portion A³ is open at one end for the reception of the hinge bolt or pin and the latter may assume any position within the length of the slot. This compensates for the different thicknesses of the door casing beyond the plane of the door and also for any variation in the setting of the hinge. It is, therefore, possible for an amateur to properly mount the stop in relation to any door to which it is to be applied. In performing this work each segment is located by engaging the slotted portion thereof with the hinge pin, after which the angle flange is secured by screws or other suitable fastening devices.

10 The angular magnitude of the segments may be varied in different constructions according to the particular position desired for the limit stop. Thus with a hinged door which is free to swing substantially through 180° the segments may be of relatively small angular magnitude, so as not to unduly restrict this movement. On the other hand, with a door in one wall adjacent to a wall at right angles thereto, the segments are of greater angular magnitude, so that the door will be stopped short of contact with the angling wall.

15 What I claim as my invention is:

20 1. A door stop comprising a pair of flanged segmental members attachable by the flanges thereof respectively to the door and casing independently of the door hinge, one of said members having a single segment provided with a series of struck-out portions and the other member being provided with a pair of segmental portions spaced to receive said single segment therebetween with a series of spaced depressions for latching engagement with said struck-out portions, said members being further provided with slotted portions for engagement with the projecting portion of the hinge bolt or pin to locate the same concentric with the axis of said bolt or pin.

25 2. A door stop comprising a pair of flanged segmental members attachable by the flanges thereof respectively to the door and casing in-

dependently of the door hinge, one of said members having a single segment provided with a series of struck-out portions and the other member being provided with a pair of segmental portions spaced to receive said single segment therebetween with a series of spaced depressions for latching engagement with said struck-out portions, said members being further provided with slotted portions for engagement with the projecting portion of the hinge bolt or pin to locate the same concentric with the axis of said bolt or pin, said depressions being radially extended with respect to the axis of the pin for engagement with said struck-out portions in slightly different positions.

3. A door stop for hinged doors comprising a pair of segmental members one frictionally embracing the other and provided with flanges for attachment respectively to the door and casing

each segmental member being further provided with an open slotted bearing portion laterally adjustable and engageable with the projecting bolt or pin of the door hinge with respect to the axis thereof for locating said segments substantially concentric with said axis.

4. A door stop for hinged doors comprising a pair of segmental members one embracing the other and fashioned for progressive latching engagement, said members being flanged for attachment respectively with the door and casing and each member being further provided with an open slotted bearing portion laterally adjustable and engageable with the projecting bolt or pin of the door hinge with respect to the axis thereof for locating said segment substantially concentric with said axis.
